UNITED STATES PATENT OFFICE.

ZACK TAYLOR AND MARTIN L. BERGMAN, OF SPOKANE, WASHINGTON.

DESIGN FOR A BATTERY-ELECTRODE.

SPECIFICATION forming part of Design No. 28,492, dated April 19, 1898.

Application filed March 3, 1898. Serial No. 672,462. Term of patent 7 years.

To all whom it may concern:

Be it known that we, ZACK TAYLOR and MARTIN L. BERGMAN, citizens of the United States, residing at Spokane, in the county of Spokane and State of Washington, have invented and produced a new and original Design for Battery-Electrodes; and we do hereby declare the following to be a full, clear, and exact description of the same, reference being had to the accompanying drawings, forming a part thereof.

Figure 1 is a top view of a battery-electrode, showing our design. Fig. 2 is a perspective view of the same, these two views being deemed necessary to fully illustrate our design.

The leading feature of our design consists in the form given to the body of the electrode, and said form has some resemblance to a horseshoe having its heels contracted toward each other, with a central tongue extended toward the rear.

The body of the electrode is substantially annular, with an opening on one side, or, as illustrated, in the form of a horseshoe having its front edge reinforced by a wide projection

C in the form of a toe-calk and its sides B contracted toward each other at the heel ends, but having an opening b between them. Between the two sides B and on a line passing 30 through said opening and crossing the calk projection C there is a tongue or finger-like projection D, extended rearwardly from the front toward the opening b, and projecting upward from the body of the electrode between 35 the inner portion of the projections C and D there is a hook e, extended in front of the projection C.

What we claim is—

The design for a battery-electrode as herein 40 shown and described.

In testimony whereof we affix our signatures in presence of witnesses.

ZACK TAYLOR.
MARTIN L. BERGMAN.

Witnesses as to Zack Taylor:

E. E. MASSON,
A. B. DEGGES.
